UNITED STATES PATENT OFFICE.

THOMAS C. DE VORE, OF CHICAGO, ILLINOIS, ASSIGNOR OF ONE-HALF TO FREDA C. DE VORE, OF CHICAGO, ILLINOIS.

AIR VALVE.

Application filed April 11, 1922. Serial No. 551,488.

To all whom it may concern:

Be it known that I, THOMAS C. DE VORE, a citizen of the United States, and a resident of the city of Chicago, county of Cook, and 5 State of Illinois, have invented certain new and useful Improvements in Air Valves, of which the following is a specification.

My invention relates to new and useful improvements in air valves, and has for its 10 principal object the provision of an improved construction of this character which will be highly efficient in use, one that can be readily assembled and which will be economical in manufacture.

15 A further contemplation of the invention is the provision for automatically closing the valve at a predetermined degree of heat and for automatically opening the valve when the degree of heat decreases. In this connection, and to carry these objects into effect, I provide tubular members carried by a hanger and an adjustable support, formed of such material that is capable of expanding and contracting when subject to heat and 25 such expansion and contracting being determined by the degrees of the heat.

Other objects will appear hereinafter.

The invention consists in the combinations and arrangements of parts hereinafter described and claimed.

The invention will be best understood by reference to the accompanying drawings forming a part of this specification, and in which,

35 Fig. 1 is a vertical sectional detail view of an air valve embodying the invention,

Fig. 2 is a top plan view of the same,

Fig. 3 is a sectional detail view of the same taken substantially on line 3—3 of Fig. 1.

40 Referring to the drawings showing the preferred form of construction, A represents an air valve embodying the invention and comprises a cylindrical body 5 open at its lower end, said opening being closed by a base cap 6 having a lateral projection 7 which is adapted to be screw-threaded in the opening of a radiator, (not shown) with which the device is associated. The upper end of the cylindrical body 5 is dome-shape, 45 as shown, and carries a valve seat 8 having a central passage 9 formed therethrough, the inner wall portions of said opening 9, that is the portion extending into the cylindrical body 5, being tapered outwardly as indicated at 10. The valve seat 8 is screw-threaded

through an opening 10' formed in the top-most or dome-shaped portion of the cylindrical body and is provided with a flange 11 adapted to seat on an annular projection or rib 12 extending around the walls of the 60 opening.

The opening 10' is provided with a closure member 13 which in this instance is in the form of a cylindrical cap having a vent 14 forming an integral part of the cap and 65 projecting laterally and downwardly from the side of the cap in spaced relation with respect to the dome-shaped portion of the cylindrical body 5, as shown.

Arranged in the base cap 6 is a disc-shaped support 15 carried by an adjustable screw 16 passing through a stuffing box 17. The disc 15 is arranged and adapted to support a tubular member 18 having its side 70 walls perforated and formed of such material that is capable of expanding and contracting when subject to heat. The tubular member 18 is strengthened at its upper edge by an annular channel-shaped ring member 19 which carries a hanger 20 formed 75 of such material as is capable of expanding and contracting when subject to heat, but which in this instance, is formed of such material that will withstand a greater degree of heat than the tubular member 18. 80

The hanger 20 in turn supports and carries a second perforated tubular member 21 arranged within the member 18 as shown, and formed of the same material. The upper edges of the tubular member 21 are also reinforced by a channel-shaped ring member 22 which carries a hanger 23 similar to the hanger 20 and formed of the same material. The hanger 23 carries a central core 24 formed of such material that will not expand or contract when subject to heat and the core is arranged and adapted to carry a valve stem 24' which works in the tapered portion of the opening 9 of the valve seat and which is adapted to close said opening 90 when the tubular members 18 and 21 expand; however, if desired, the core 24 can be formed of material similar to the material from which the tubular members are formed. The valve stem 24' carries a dish-shaped annular member 25 which serves the purpose of a baffle plate for directing the steam or water vapor against the perforated tubular members 18 and 21. To prevent the valve 100 stem 24' from becoming wedged in the open- 105

ing 9, I provide an expansion spring 26 which embraces the valve stem and seats against the valve seat 8 and baffle plate 25.

In use, my air vent as herein illustrated and described, is mounted in the usual way on a radiator or the like through the medium of the stem 7 and when the steam or water vapor from the radiator enters the valve, the tubular members 18 and 21 will expand according to the degree of the heat, and should the degree be greater than the members can withstand, the said members, through expansion will cause the valve stem to close the opening 9 of the valve seat 8, thus preventing the exit of the air from the radiator. On the other hand, when the radiator becomes air bound and the steam or water vapor cools, the tubular members will contract, thus opening the passage of the valve seat 8 permitting the air to find an exit through the passage 14. By means of the set screw 16 and disc support 15, the distance between the valve stem 24' and the outer portion of the opening 9 can be readily adjusted and by such adjustment for example should the valve stem be adjusted any great distance from the opening, the expansion of the tubular members 18 and 21 will doubtlessly have to be greater in order to close the opening, or should the valve stem be adjusted nearer the opening, the expansion of the tubular members will doubtlessly be less than when the valve stem is farther away from said opening.

In constructing my improved air valve, I have taken into consideration that it often becomes necessary for one who is not a mechanic, to adjust or repair the various parts of the valve, and in order that such repairs can be made, I have invented a valve which comprises parts, such that the mounting and arrangement of which are simple and will enable anyone not skilled in the art to take the valve apart, make such repairs as may be necessary and reassemble the valve.

I have found by experience that by forming the vent of the cap 13 in the manner illustrated in Fig. 1, that the singing noise which accompanies the discharge of the air from the valve is greatly obviated, if not entirely, and also by this arrangement particles of dust are prevented from gaining entrance into the cap and settling around the valve seat until the passage of air through the opening of the valve seat is prevented, this being the case where the vent of the cap is formed in alignment with the opening of the valve seat.

While I have illustrated and described the preferred form of construction for carrying my invention into effect, this is capable of variation and modification without departing from the spirit of the invention. I, therefore, do not wish to be limited to the precise details of construction set forth, but

desire to avail myself of such variations and modifications as come within the scope of the appended claims.

Having described my invention, what I claim as new and desire to secure by Letters Patent is:

1. An air valve of the class described including a casing provided with an air vent, a core having a relatively small coefficient of expansion within the casing and provided with means for closing the vent, tubular members within the casing, and supporting means for the core having portions seated on the top edges of the inner of the tubular members and having a portion providing a seat for the core. 75

2. An air valve of the class described including a casing provided with an air vent, a core within the casing carrying means for controlling passage through the vent, tubular members of expansible material within the casing, and arranged concentrically with respect to each other, channel shaped ring members at the upper peripheral edges of the tubular members, a support carrying the core and having its ends resting on the ring member of the adjacent tubular member, and a support carrying said tubular member and having its ends resting on the ring member of the other tubular member. 90 95

3. An air vent of the class described comprising a casing having an air vent formed therein; a valve controlling said vent; an adjustable support carried by said casing; an expansible tubular member carried by said support; a hanger carried by said tubular member; a core of relatively small coefficient of expansion carried by said hanger; and a valve stem carried by said last named support for controlling said valve. 100 105

4. An air valve including a casing provided with an air vent and a passage in communication with the vent extending outwardly and downwardly with respect to the casing, a core of relatively small coefficient of expansion within the casing and carrying a member for closing the vent, tubular members having perforations formed in the walls thereof carrying said core and adapted under influence of steam entering said casing to move the core to bring the vent controlling member into position to close the vent. 110 115

5. An air valve of the class described comprising a casing having an air vent formed therein; a disc-shaped support carried by said casing; a perforated tubular member of expansible material carried by said support; a hanger carried by said tubular member; another tubular member of expansible material carried by said hanger; a hanger carried by said second named tubular member; a core of non-expansible material carried by said second named 120 125 130

hanger; a valve stem carried by said core for opening and closing said valve; and means carried by said valve stem for directing steam or the like against said tubular members.

6. An air valve of the class described comprising a casing having an air vent formed therein; an adjustable disc-shaped support carried by said casing; a perforated 10 tubular member of expansible material carried by said support; a hanger carried by said tubular member; another tubular member of expansible material carried by said hanger; a hanger carried by said second 15 named tubular member; a core of non-ex-

pansible material carried by said second named hanger; a valve stem carried by said core for opening and closing said valve; means carried by said valve stem for directing steam or the like against said tubular members; and a spring member embracing said valve stem for forcing said stem from engagement with said valve. 20

In testimony whereof I have signed my name to this specification in the presence of 25 two subscribing witnesses.

THOMAS C. DE VORE.
